ATTORNEYS

UNITED STATES PATENT OFFICE

2,517,271

SHIRT

George Augusto, Paterson, N. J.

Application April 7, 1950, Serial No. 154,539

2 Claims.

(Cl. 2—115)

1

This invention relates to improvements in closed-front shirts, such as men's outer shirts, whether closed by a slide-fastener zipper or other means, the primary object of the invention being to provide means in a closed-front shirt whereby the end of a necktie when worn with such a shirt can be tucked beneath the shirt front and an ordinary tie clasp can be used to hold the tie end on the outer side of the shirt front.

Another important object of the invention is the provision of openings in the under flap of a slide-fastener or other closed shirt to provide for insertion therethrough of a necktie end or an element of a tie clasp, the said openings being concealed by the outer or overlying flap of the shirt.

Other important objects and advantageous features of the invention will be apparent from the following description and the accompanying drawings, wherein, merely for purposes of illustration, specific embodiments of the invention are set forth in detail.

In the drawings, wherein like numerals designate like parts throughout the several views:

Figure 1 is a fragmentary front elevation of a closed-front shirt and associated necktie, and showing in dotted lines the insertion of the free end of the tie behind the shirt front in the manner provided by the present invention;

Figure 2 is an enlarged fragmentary front elevation, showing the flaps of a slide-fastened closed shirt front separated and the under flap provided with an opening;

Figure 3 is an enlarged fragmentary horizontal section taken on the line 3—3 of Figure 1;

Figure 4 is a fragmentary front elevation, on a reduced scale, showing the provision of separate openings for the tie and for a tie clasp.

Referring in detail to the drawings, the numeral 5 generally designates a man's outer shirt having the front 6 including the outer or overlying flap 7 and the inner or underlying flap 8, the flap 7 substantially overlapping the flap 8. The means, generally designated 9, connecting the flaps together throughout their length, leaving no gaps or spacings, such as are incidental to open-front or buttoned shirts, can be of any suitable form, but is herein illustrated as a slide-fastener having rows of components 10 and 11 on the outer and inner flaps 7 and 8, respectively, connectible by the slider 12.

At a proper or desired distance below the shirt collar 13 the inner flap 8 is formed with a vertically elongated slit 14 provided with bound edges, as indicated at 15, to pass the free end 16 of the tie 17 under the shirt front 6, with the

2

shirt front 6 closed by the slide-fastener 9. The slit 14 is positioned in the under flap 8 parallel to the slide-fastener component 11, and is spaced between the slide-fastener component 11 and the free edge 18 of the under flap 8, as shown in Figure 2.

With this arrangement of the slit 14, the outer flap 7 overlies and conceals the slit 14, the free edge 19 of the outer flap 7 being extended to cover the entire width of the under flap 8. Thus, the slit 14 is concealed by the outer flap 7 and is not visible when not in use. When the free end 16 of the tie 17 is inserted rearwardly through the slit 14, as shown in dotted lines in Figures 1 and 4, only a minor portion of the outer flap 7 is slightly displaced from its normal flat lying position.

To provide for use of an ordinary tie clasp 20 to hold the free end 16 of a tie 17 flatwise on the shirt front 6, another slit 21 similar to the slit 14 and similarly placed in the under flap 8 is provided in the under flap 8 at the proper or desired position, spaced below the slit 14. The lower slit 21 enables the rear arm 22 of the tie 20 clasp to be inserted behind the under flap 8, with the outer tie clasp corner 23 engaging the front of and compressing the tie end against the outer flap 7 and adjacent portions of the shirt front 6.

I claim:

30 1. In a shirt, a front having overlapping inner and outer flaps having free edges, means connecting said flaps together throughout their length, said means being laterally spaced from the free edges of the flaps, and slit means formed in said inner flap between said connecting means and the free edge of said inner flap and concealed by said outer flap.

35 2. In a shirt, a front having overlapping inner and outer flaps having free edges, means connecting said flaps together throughout their length, said means being laterally spaced from the free edges of the flaps, and slit means formed in said inner flap between said connecting means and the free edge of said inner flap and concealed by said outer flap, said slit means comprising an upper tie end-receiving slit and a lower slit for passing an arm of a tie clasp.

GEORGE AUGUSTO.
